UNITED STATES PATENT OFFICE

KARL KREUTZER, OF NUREMBERG, GERMANY, ASSIGNOR TO FIRM J. S. STAEDTLER, OF NUREMBERG, GERMANY

DESIGN FOR A DRAWING PENCIL

Application filed February 7, 1931, Serial No. 38,579, and in Germany September 2, 1930. Term of patent 14 years.

To all whom it may concern:

Be it known that I, KARL KREUTZER, a citizen of Germany, residing at Nuremberg, (Bavaria), Germany, have invented a new, original, and ornamental Design for a Drawing Pencil, of which the following is a specification, reference being had to the accompanying drawings, forming part thereof.

Figure 1 is a front view of a drawing pencil showing my design; Figure 2 is an end view; and Figure 3 is a rear view.

I claim:—

The ornamental design for a drawing pencil, as shown.

In testimony whereof I affix my signature.
KARL KREUTZER.
